(57) **CLAIM**

The ornamental design for a chair, as shown and described.

DESCRIPTION

This application is related to concurrently filed design applications, Ser. Nos. 29/140,830 and 29/140,828.

FIG. 1 is a front elevational view of a chair showing my new design;

FIG. 2 is a top plan view thereof;

FIG. 3 is a rear elevational view thereof;

FIG. 4 is a bottom plan view thereof;

FIG. 5 is a right side elevational view thereof;

FIG. 6 is a vertical sectional right side view taken along the line 6—6 FIG. 1;

FIG. 7 is a horizontal sectional plan view taken along the line 7—7 in FIG. 1;

FIG. 8 is a vertical sectional front view taken along the line 8—8 in FIG. 2;

FIG. 9 is a front perspective view of the chair; and,

FIG. 10 is a rear perspective view thereof.
